[57] CLAIM

The ornamental design for a dice scrambler, as shown and described.

DESCRIPTION

FIG. 1 is a perspective view of a dice scrambler showing my new design;

FIG. 2 is a top plan view thereof;

FIG. 3 is a front elevation view thereof;

FIG. 4 is a right side elevational view thereof, the opposite side being a mirror image;

FIG. 5 is a rear elevational view thereof; and,

FIG. 6 is a bottom plan view thereof.

The broken line showing of the dice in FIG. 1 are for illustrated purposes only and forms no part of the claimed design.
